[57] CLAIM

The ornamental design for a multimode lighting fixture, substantially as shown and described.

DESCRIPTION

FIG. 1 is a pictorial view of a multimode lighting fixture incorporating our new design.

FIGS. 2, 3 and 4 are, respectively, front, side and top plan views thereof on an enlarged scale.

FIG. 5 is a pictorial view of a modified form of the multimode lighting fixture.

FIGS. 6, 7 and 8 are, respectively, front, side and top plan views of the fixture shown in FIG. 5 on an enlarged scale.

The rear is flat and plain. The bottom is identical to the top. The front panel and the side panels contrast in color.
